FIXED-BASE AVIATION TRAINER

Laimons E. Drupa and Richard L. Strong, Binghamton,
N.Y., assignors to General Precision Systems Inc., a
corporation of Delaware

Filed Mar. 3, 1967, Ser. No. 6,044

Term of patent 14 years

(Cl. D71—1)

FIG. 1

FIG. 2

FIG. 3

FIG. 1 is a side elevational view of a fixed-base aviation trainer according to this invention;

FIG. 2 is a top plan view of the fixed-base aviation trainer of FIG. 1; and

FIG. 3 is a front elevational view of the fixed-base aviation trainer of FIG. 1.

We claim:

The ornamental design for a fixed-base aviation trainer, as shown.
